UNITED STATES PATENT OFFICE.

RENY A. BREAKFIELD, OF MADRID, IOWA.

APPARATUS FOR TREATING RHEUMATISM.

1,032,324.

Specification of Letters Patent.

Patented July 9, 1912.

Application filed March 20, 1912. Serial No. 685,090.

To all whom it may concern:

Be it known that I, RENY A. BREAKFIELD, a citizen of the United States, residing at Madrid, in the county of Boone and State 5 of Iowa, have invented a new and useful Apparatus for Treating Rheumatism, of which the following is a specification.

The object of my invention is to provide a device of durable, simple and inexpensive 10 construction, whereby a slight amount of electricity may be generated from certain metals, by utilizing the moisture and acids of the skin.

My invention consists in certain details, 15 in the arrangement, construction, and combination of the various parts of my device, whereby the objects contemplated are attained, as hereinafter more fully set forth, pointed out in my claims, and illustrated in 20 the accompanying drawings, in which—

Figure 1 shows an end elevation of a device embodying my invention. Fig. 2 shows a horizontal sectional view through the same. Fig. 3 shows a horizontal sectional 25 view of part of the device on the line 3—3 of Fig. 1.

In the accompanying drawings, I have used the reference numeral 10 to indicate a sheet of zinc rectangular in form and 30 preferably considerably longer than it is wide. Adjacent to the sheet of zinc, I place a sheet of copper 11 of the same length as the strip of zinc and somewhat wider. At the sides the strips of zinc and copper are 35 bent around copper wires 13 which run longitudinally along the sheets of zinc and copper as shown in Fig. 2. The sheet of zinc 10 extends part way around the copper wire and the sheet of copper 11 extends 40 practically the full distance around said copper wire. The copper sheet being made of somewhat soft material, forms a convenient means for holding the zinc sheet and the copper wires together. The plate 45 of copper is designed to be placed in the middle of the back and the wires 13 are of sufficient length to extend over the shoulders and around the waist, respectively to the

front of the body where they may be fastened together in the manner hereinafter 50 described.

Other materials than copper and zinc may be used if they are suitable for the causing of an electrical reaction when subjected to moisture and acid and the form of my device may be varied although I think it advisable to have the zinc and copper plates wrapped around the copper wire or the like with the copper plate extended farther around the wire than the zinc plate in order 55 to produce a construction favorable for permitting the moisture from the body to follow the copper wire along the edges of the copper plate. The moisture thus travels along the edges of the zinc and copper 60 plates.

For securing the wires 13 together in front of the body, I have provided the following means: A plate or block 14 is provided with loops 15 to which the wires 70 which go over the shoulders are secured. Extending longitudinally through the plate 14 is a slot or passage 16. On the side of the plate 14 opposite the loops 15, I provide lugs 17, extending into said slot 16. The 75 free ends of the parts of the wires 13 which pass around the waist are provided with notches 18. When the free ends of said wires are inserted into said slot, the notches 18 engage the lugs 17 as shown in Fig. 1. 80 By pressing the free ends of the wires 13 together, they may be removed from the slot 16.

I claim as my invention:

1. A zinc plate, a copper plate somewhat 85 wider than said zinc plate, placed adjacent thereto, copper wires, the sides of said zinc and copper plates being bent around said wires, with the sides of the copper plate extending farther around said wire than the 90 sides of the zinc plate.

2. A zinc plate, a copper plate somewhat 95 wider than said zinc plate, placed adjacent thereto, copper wires, the sides of said zinc and copper plates being bent around said wires, with the sides of the copper plate

extending farther around said wire than the sides of the zinc plate, and means for securing the free ends of said copper wires together in front of the body of a wearer, said means comprising a block secured to one end of each of the copper wires, said block being provided with a longitudinal slot and with opposite lugs extending into said slot,

the other ends of said copper wires being provided with notches.

Des Moines, Iowa, March 16, 1912.

RENY A. BREAKFIELD.
